DIAL SWITCHING TOLL SYSTEM

Application filed November 12, 1930, Serial No. 495,199; and in Great Britain November 13, 1929.

This invention relates to telephone systems in which automatic switches are used in the establishment of connections and more particularly but not exclusively to such systems in which facilities are provided for extending connections over toll lines.

The object of the invention is to provide in a system of this character more efficient means whereby toll calls may be automatically established without the services of operators in the order in which the calls arrive.

It has been the practice in the past for toll calls to be extended by an operator at a toll exchange. A calling subscriber requiring a toll connection asks the "A" operator for the required number or alternatively for the toll exchange and he is thereupon switched through by way of a recording trunk to the

20 toll exchange where the recording operator writes out a ticket giving the numbers of the wanted and calling parties and passes it to the toll operator in charge of the toll line leading to the required exchange. The calling party is then instructed to hang up. During slack periods the toll operator can immediately ring through to the distant operator on the toll line and ask for the wanted number. During rush hours all the trunks at 25 the toll operator's position will be engaged and the ticket is added to those already awaiting their turn. When, however, the toll operator has asked for a wanted number over a trunk she then calls back to the calling subscriber over a toll switching trunk and if the wanted subscriber has replied she connects the two parties.

The above method necessitates a considerable amount of work for each connection on 30 the part of the toll operator and in consequence such operators can only deal with a very limited number of toll calls. It follows therefore that the operating costs are high and the operating efficiency low.

45 It has also been proposed to use a full automatic switching equipment for the establishment of toll connections in which for example the calling subscriber dials the wanted number into a local register sender, which upon having stored the said single call

or part thereof, tries to extend the call to a toll line leading to the desired exchange. It will readily be understood by those skilled in the art, that in order to prevent difficulties in handling such calls, such as delays during rush hours, it will be necessary to provide an adequate number of toll lines outgoing in the desired directions. The number of lines must be such that the local connecting circuit to which the register is attached during the setting up of the connection can readily find access to a toll line and in consequence will not hold the local register sender in use for a long period. For these reasons the number of toll lines should be adapted to the maximum number of calls outgoing in a particular direction during the rush hours. This, however, is not economical.

50 In accordance with the present invention, one embodiment of which is disclosed herein by way of illustration, the delay and expense incident to the employment of operators for establishing toll connections in an automatic exchange area is obviated. The invention has been illustrated by the single figure of the 55 accompanying drawing. It should be understood, however, that the invention and the various features thereof is not limited to this particular embodiment but may be applied to any telephone or remote control system in which the connections are established by 60 means of automatic switching apparatus. It should also be understood that only such parts of the system are shown in the drawing and described hereinafter as are absolutely necessary for a clear understanding of the 65 invention.

70 Referring now to the figure a calling subscriber S upon initiating a toll call is connected over a line finder switch LF to a link circuit which thereupon becomes connected to an idle local registering and controlling mechanism such as R. It should be noted that the local equipment shown on the left-hand side of the drawing and comprising the switch 75 LF and selector OS, the register selector RS 80 and the registering mechanism R form no part of the present invention and may be of any suitable type. For example the calling line may be connected to the brushes of a pre- 85 90 95 100

selector and the local registering mechanism may be dispensed with.

As soon as an idle registering mechanism has been selected, and is ready to take up the series of impulses representing the toll call designation, a dialing tone is transmitted to the calling subscriber's station. As the calling subscriber desires a toll connection he will first dial a prefix indicating such a connection. This prefix may comprise three digits such as TOL or TRU. When this prefix has been received by the local registering mechanism this registering mechanism will immediately start to operate the selector switch OS 15 to select a free trunk leading to the toll exchange. In the case under consideration the subscriber will be instructed to dial only said prefix and to await a second dialing tone which will be given as soon as a line finder 20 such as FS has picked up the calling trunk and connected thereto an auxiliary register sender mechanism TR. The calling subscriber thereupon dials the wanted subscriber's number, for example, MAN 8312 and 25 follows it immediately by his own number, for example, CEN 7345.

As a modification of the invention, however, the local registering mechanism R may be arranged to receive the complete toll call 30 designation, that is to say the said prefix and the calling subscriber's number as well as the called subscriber's number. As the total number of digits will exceed the capacity of the local registering mechanism R, an auxiliary 35 registering mechanism may be provided which is adapted to be connected to the local registering mechanism when a prefix indicating a toll call has been received in the local registering mechanism R. This prefix 40 will cause a finder switch to hunt for that particular registering mechanism and to connect it with the said auxiliary registering mechanism in which the surplus of digits may be stored. The auxiliary registering 45 mechanism and the circuit arrangements in the local registering mechanism may be similar to that disclosed in the application of C. E. Stevens and M. den Hertog Serial No. 459,331, filed June 5, 1930.

It will be assumed, however, that only the toll prefix will be stored in the local registering mechanism R. In this case this registering mechanism starts the selection of a free trunk through the operation of selector OS 55 immediately after the second digit has been received and stored therein. This selection is carried out in the well known manner and need not be described herein. It should be noted, however, that although only one selector OS in the originating office has been disclosed for extending a connection to the desired toll exchange, shown in the drawing, this connection may be established over a plurality of such selectors as is well known in 60

the art, the number of such selectors being determined by the particular circumstances.

As soon as a connection has been extended by a selector OS in the originating exchange to a trunk line outgoing to the toll exchange, a line finder FS is started to hunt for the calling or outgoing trunk line in a well known manner. When said trunk line has been found, a dialing tone is transmitted to the calling subscriber from the auxiliary registering mechanism TR and the subscriber will thereupon proceed with the dialing operation. In the meantime the local link circuit has been connected through the switch OS and thence to the outgoing trunk circuit and therefore the impulses dialed by the calling subscriber will be transmitted directly to said auxiliary registering mechanism TR. For this purpose suitable impulse repeating devices of any well known construction may be arranged in the local link circuit. 75

The auxiliary registering mechanism TR is so arranged that the series of impulses representing the wanted subscriber's number are received by a translating registering device which may be of any well known type. Means are also provided therein whereby on the completion of the registering of the wanted subscriber's number a change over is effected to route the series of impulses representing the calling subscriber's number to another registering device. This latter device may be a straightforward step-by-step register or a register in which switches are caused to hunt under the control of a counting relay chain in the well known manner. The auxiliary registering mechanism TR is further equipped with a time alarm switching mechanism which operates if any delay occurs or only a partial call is set up. This time alarm switching mechanism when operated causes the immediate release of the auxiliary registering mechanism TR and the local connecting circuits. The circuit arrangement, however, may be such that upon the release of the auxiliary registering mechanism, the subscriber is connected through to an operator in the well known manner. If, however, a complete call has been set up, that is if the complete designations of the called and calling parties have been stored in the register the auxiliary registering circuit starts to secure access over a selector SS and a trunk ST to a punching mechanism PM which is individual to a group of toll lines incoming to the required toll exchange or to an intermediate switching exchange required for the call. Each auxiliary registering mechanism TR has access to one such trunk ST only for each group of outgoing toll lines. 115

The punching mechanism PM is of the type used in telegraph systems which punches upon a tape T or a card a series of holes forming a record of the call. The operating speed 120

of this punching mechanism is very high and it is therefore possible to discharge the auxiliary registering mechanism TR after a very short interval. Therefore one such mechanism PM will suffice for the whole of the calls and to serve a small group of trunks. In cases where large groups of trunks are available, a distributing mechanism DM which may conveniently consist of a group of relays 5 is provided to allocate a number of punching mechanisms such as PM, P'M, P₂M₂, to incoming calls in turn. After a record of the call has been punched upon the tape T by the punching mechanism PM and 10 the auxiliary registering mechanism TR has been discharged, no apparatus in the originating office is maintained on the connection, except the line switches LF and FS, the selector OS and the switch SS. 15 The tape T or the card on which the designations of the called and the calling parties have been stored, is fed through a sending mechanism SM which is individual to the required group of toll lines and which is 20 arranged to be connected to a toll line over a switch TS immediately one becomes free. Associated with each toll line is a connecting mechanism CM which consists of suitable switching and signaling relays for receiving 25 and transmitting signals over the toll line. Each such mechanism is associated with a hunting switch TSF which is arranged to pick up a toll switching trunk immediately 30 the connecting mechanism CM is seized. Located at a monitoring operator's position OPM is a printing mechanism of the type used in printing telegraph systems 35 which prints upon a tape the digits of the numbers of the calling and called parties re- 40 transmitted by the sending mechanism SM under control of the tape T. The record thus printed serves as a charge ticket for the established toll connection. The impulses 45 transmitted by the sending mechanism SM corresponding to the called party's number also pass through the connecting mechanism CM and are recorded in the registering mechanism R₁ local to the called party's exchange, 50 said registering mechanism being associated with the connecting mechanism CM through the operation of the line finder TC and a register selector R'S'. At the conclusion of the transmission of 55 the digits of the wanted party's number a change-over is effected by the mechanism CM preferably by means of a change-over signal punched on the tape T and the remaining impulses recorded on the tape are 60 sent out over the switch TSF and the toll switching trunk and the outgoing toll switch OT to connect up the calling subscriber by means of the local automatic switching apparatus, LS₁, LS₂ and FL. Thereafter the 65 sending mechanism SM is immediately re-

leased and the mechanism CM awaits response by the two subscribers.

At the called party's exchange, when the toll trunk line has been extended thereto through the connecting mechanism CM, the line finder TC associated with the link circuit CO is started to find the calling toll line and a register sender selector R'S' associated with said link circuit selects an idle registering mechanism R₁. As soon as the selecting mechanism R₁ becomes associated 70 a signal is transmitted to the sending mechanism SM to cause it to start the retransmission of impulses corresponding to the called party's number to the registering mechanism R₁ followed by the retransmission of impulses for selecting the calling party's line. By means of a simple relay device in the link circuit CO a signal is operated 75 before the monitoring operator MO. The impulses received by the registering mechanism R₁ are effective in the well known manner to set a train of switches, one of which is shown at C to extend the toll connection to the wanted party's line. 80

In the event of the called subscriber being busy, a relay is operated in the link circuit CO and as a result a signal is sent over the toll line which actuates a device at the connecting mechanism CM to attract the attention of the monitoring operator at OPM. The monitoring operator listens in on the connection, hears the busy tone and promptly rings over the toll line to obtain the attention of the operator MO and then requests her to offer the call to the wanted subscriber whose number can be readily obtained from the typed tape at the printer of position OPM. If the called subscriber is busy, a busy flash relay in the connecting mechanism CM is operated and the operator at the position OPM is brought in on the connection as before. The operator at position OPM now rings up the calling subscriber to inform him that the called subscriber is busy and thereupon the release of the connection takes place in the well known manner. 90 95 100 105 110

The record on the tape at the operator's position OPM gives a complete record of the call and a record of the total number of calls over a particular toll line and enables the operator to make notes regarding a call actually being recorded upon the tape and finally permits the station called and the condition of the toll line that is busy or free to be readily observable from the monitoring operator's position OPM. 115 120

In accordance with a modification of the present invention arrangements might also be made whereby a subscriber could obtain toll dialing facilities only by first dialing his own number, such calling subscriber being subsequently recalled over a train of switches which provides the toll dialing fa- 125 130

cilities. In accordance with a further modification of the invention, the calling subscriber might not be required to dial his own number, suitable arrangements being provided whereby a record of his number could be set up in the register TR by sending or other suitable mechanism, the operation of which would be determined by the position of the calling line in the bank of the line 10 finder switch LF.

What is claimed is:

1. In an automatic telephone system, calling lines, called lines, automatic switching devices for extending connections to said 15 called lines, a storing mechanism for storing the designations of called lines in the order in which calls therefor are initiated by said calling lines, and a sending mechanism individual to said storing mechanism for 20 successively controlling said switching devices in accordance with the designations stored in said storing mechanism.

2. In an automatic telephone system, calling lines, called lines, automatic switching devices for extending connections to said called 25 lines, a storing mechanism for storing the designations of called lines in the order in which calls therefor are initiated by said calling lines, and a sending mechanism individual to said storing mechanism effective 30 for controlling said switching devices in accordance with the designation of one called line stored in said storing mechanism while said storing mechanism is successively storing 35 the designations of called lines for later initiated calls.

3. In an automatic telephone system, calling lines, called lines, automatic switching devices for extending connections to said 40 called lines, a storing mechanism comprising a tape and a tape punching device for storing the designations of called lines in the order in which calls therefor are initiated by said calling lines, and a sending mechanism individual to said storing mechanism for 45 successively controlling said switching devices in accordance with the designations punched in said tape.

4. In an automatic telephone system, calling lines, called lines, a storing mechanism for recording the designations of calling and called lines, a sending mechanism, switching devices for extending connections in opposite directions to a calling line and to a called 50 line and means under the control of said storing and sending mechanisms for operating said switching devices.

5. In an automatic telephone system, calling lines, called lines, a storing mechanism for recording the designations of calling and called lines, means controlled by successively calling lines to seize said storing mechanism and to cause said storing mechanism to successively record the designations of said calling 55 lines and the designations of called lines

called thereby, a sending mechanism, switching devices for extending connections in opposite directions to calling lines and called lines called thereby, and means under the control of said sending mechanism for operating said switching devices to establish connections between said calling and called lines in the order in which said line designations have been stored in said storing mechanism. 70

6. In an automatic telephone system, calling lines, called lines, a storing mechanism for recording the designations of calling and called lines, means controlled by successively calling lines to seize said storing mechanism and to cause said storing mechanism to successively record the designations of said calling lines and the designations of called lines called thereby, a sending mechanism, switching devices for extending connections in opposite directions to calling lines and called lines called thereby, and means under the control of said sending mechanism for operating said switching devices to establish a connection between a calling line and a called line in accordance with a record stored in 80 said storing mechanism, while said storing mechanism is effective to store the record of a subsequently initiated call. 90

7. In an automatic telephone system, calling lines, called lines, a storing mechanism comprising a tape and a tape punching device for storing the designations of calling and called lines, means controlled by successively calling lines to seize said storing mechanism and to cause said punching device to successively punch in said tape the designations of said calling lines and the designations of called lines called thereby, a sending mechanism individual to said storing mechanism, automatic switching devices 100 for extending connections in opposite directions to calling lines and called lines called thereby, and means controlled by said sending mechanism for successively controlling said switching devices in accordance with 105 the designations punched in said tape. 110

8. In an automatic telephone system, calling lines, called lines, automatic switching devices for extending connections to said called lines, a storing mechanism for storing the designations of called lines in the order in which calls therefore are initiated by said calling lines, a sending mechanism individual to said storing mechanism for successively controlling said switching devices in accordance with the designations stored in said 115 storing mechanism, a monitoring operator's position, and means at said position under the control of said storing mechanism for making a printed record of the designations 120 of called lines in the order in which connections are established by said sending mechanism. 125

9. In an automatic telephone system, calling lines, called lines, a storing mechanism for 130

recording the designations of calling and called lines, means controlled by successively calling lines to seize said storing mechanism and to cause said storing mechanism to successively record the designations of said calling lines and the designations of called lines called thereby, a sending mechanism, switching devices for extending connections in opposite directions to calling lines and called lines called thereby, means under the control of said sending mechanism to operate said switching devices to establish connections between calling and called lines in the order in which said line designations have been stored in said storing mechanism, a monitoring operator's position and means at said position under the control of said storing mechanism for making a printed record of the designations of calling lines and the lines called thereby.

10. In an automatic telephone system, calling lines, called lines, a storing mechanism for recording the designations of calling and called lines, means controlled by successively calling lines to seize said storing mechanism and to cause said storing mechanism to successively record the designations of said calling lines and the designations of called lines called thereby, means for disconnecting a calling line from said storing means as soon as the designations appertaining to the call initiated by said calling line have been stored, a sending mechanism, switching devices for extending connections in opposite directions to calling lines and called lines called thereby, and means under the control of said sending mechanism for operating said switching devices to establish connections between calling and called lines in the order in which said line designations have been stored in said storing mechanism.

11. In an automatic telephone system, calling lines, called lines terminating in a toll office, toll lines incoming to said office, automatic switching devices in said office for extending connections from said toll lines to said called lines, a storing mechanism for recording the designations of toll cords initiated by said calling lines for said called lines in the order in which said calls are initiated by said calling lines, a sending mechanism individual to said storing mechanism, means for associating said sending mechanism with said toll lines as fast as said toll lines become free, and means effective upon the successive association of said sending mechanism with free toll lines for controlling said switching devices in accordance with the toll call designations recorded by said storing mechanism and in the order in which said designations have been recorded.

12. In an automatic telephone system, calling lines, called lines terminating in a toll office, toll lines incoming to said office, automatic switching devices in said office for ex-

tending connections from said toll lines to said called lines, automatic switching devices for extending connections from said toll lines to said calling lines, a storing mechanism for recording the designations of toll calls initiated by said calling lines, said designations including the designations of said calling lines and the designations of the called lines called thereby, a sending mechanism individual to said storing mechanism, means for associating said sending mechanism with said toll lines as fast as said toll lines become free, and means effective upon the successive association of said sending mechanism with free toll lines for controlling said switching devices in accordance with the toll line designations recorded by said storing mechanism to establish connections between said calling and called lines in the order in which said designations have been recorded.

13. In an automatic telephone system, calling lines, terminating in a local office, called lines terminating in a toll office, toll lines outgoing from said local office, means in said local office responsive to the dialing of a toll office code for extending connections from calling lines to outgoing toll lines, toll lines incoming to said toll office, automatic switching devices in said toll office for extending connections from said toll lines to said called lines, automatic switching devices for extending connections from said incoming toll lines to said calling lines, toll call designation recording means associative with said outgoing toll lines, a storing and sending mechanism successively associative with said recording means and with said incoming toll lines, and means controlled by said storing and sending mechanism for successively establishing connections between calling and called lines in accordance with the designations set up in said recording means and in the order in which said storing and sending mechanism becomes associated with said recording means.

14. In an automatic telephone system, calling lines terminating in a local office, called lines terminating in a toll office, toll lines outgoing from said local office, means in said local office for extending connections from calling lines to outgoing toll lines, toll lines incoming to said toll office, automatic switching devices in said toll office for extending connections from said toll lines to said called lines, automatic switching devices for extending connections from said incoming toll lines to said calling lines, toll call designation recording means associative with said outgoing toll lines, a storing and sending mechanism successively associative with said recording means and with said incoming toll lines, means controlled by said recording means to transfer said toll call designations to said storing means, means operative following the transfer of a designation for releasing the connection between a calling line and the

particular recording means associated therewith, and means controlled by said storing and sending mechanism for successively establishing connections between calling and called lines in accordance with designations transferred thereto and in the order in which said storing and sending mechanism becomes associated with said recording means.

15. In an automatic telephone system, calling lines, called lines, a plurality of storing mechanisms for recording the designations of calling and called lines, means controlled by successively calling lines to seize said storing mechanisms in rotation and to cause said storing mechanisms to successively record the designations of said calling lines and the called lines called thereby, a sending mechanism individual to each storing mechanism, switching devices for extending connections in opposite directions to calling lines and called lines called thereby, and means under the control of a sending mechanism for operating said switching devices to establish connections between calling and called lines in the order in which line designations have been stored in the storing mechanism to which it is individual.

16. In a telephone system in which connections are established between subscribers' lines by means of automatic switching mechanism, the method of handling calls initiated by subscribers for distant toll points which consists in automatically punching a tape under the remote control of the calling subscriber listing the number of the line wanted and the number of the calling line, and automatically controlling said switching mechanism in accordance with the record punched in said tape to extend a connection from a toll line in opposite directions to said calling line and to said wanted line.

17. In a telephone system in which connections are established between subscribers' lines by means of automatic switching mechanism, the method of handling calls initiated by subscribers for distant toll points which consists in automatically punching a tape under the remote control of the calling subscriber listing the number of the line wanted and the number of the calling line, automatically controlling said switching mechanism in accordance with the record punched in said tape to extend a connection from a toll line in opposite directions to said calling line and to said wanted line, and automatically printing a toll ticket under the control of said tape.

18. In a telephone system in which connections are established between subscribers' lines by means of automatic switching mechanism, the method of handling calls initiated by subscribers for distant toll points, which consists in automatically punching a tape under the remote control of calling subscribers to successively record the data of

the successively initiated toll calls, the data for each call comprising the number of the line wanted and the number of the calling line, feeding said tape into a sending mechanism, and successively controlling said sending mechanism under the control of said tape to extend toll connections between calling and called lines over said switching mechanism in the order in which said toll calls were initiated.

In witness whereof, we hereunto subscribe our names this 14th day of October, 1930.
